UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 12,338, dated July 5, 1881.

Application filed May 6, 1881. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression; and it consists of a design for a font of printing-type to be used for ornamental surroundings for printed matter.

The motive is Egyptian, and I will describe the various members of which the font is composed.

Nos. 1 and 2 are sections of molding ornamented upon the face by the lotus-bud-like ornaments.

No. 3 is a short horizontal line.

20 No. 4 is a longer horizontal line.

No. 5 is a line inclined to the left, met at its lower termination by a horizontal line extending to the right.

No. 6 is the reverse of No. 5.

25 Nos. 7, 8, and 9 are representations of Egyptian hieroglyphics.

No. 10 is a section of molding ornamented upon its face by the lotus-like ornament and the semi-elliptical curves below.

30 No. 11 is a representation of a scarabaeus covered with wings; in the center the sun and the asps.

Nos. 12 and 13 are sections which, united, form a capital resembling the composite order of architecture.

35 Nos. 14 and 15 are sections of moldings ornamented upon the face by the short vertical lines placed at intervals and below by the semi-circular lines.

40 No. 16 is a representation of a section of a molding with a scarabaeus covered with wings; in the center the sun and the asps.

Nos. 17 and 18 are sections which, united, form a capital.

45 Nos. 19 and 20 are sections of compound molding, the upper portion composed of a light horizontal line, a short distance below which is placed a heavy horizontal line. Below this are two horizontal lines shaded upon the

50 upper portion of face by a heavy line, and be-

low this by a series of short vertical lines; below this a similar molding.

Nos. 21 and 35 are groups of columns, with smaller columns in perspective, the main columns adorned with hieroglyphics.

55 No. 22 is an Egyptian column of the seventh order of Egyptian architecture.

No. 23 is a capital of the sixth order of Egyptian architecture.

Nos. 24 and 25 are sections of a border. No. 60 24 has the inclined lines upon the left ornamented upon the space between them by the central bar, from which extend, upward to the left and downward to the right, the figures formed by the inclined lines, and is also shaded. 65 To the right of this figure extends a series of pointed figures shaded on the face by a series of short vertical lines, gradually shortening as they approach the central points, and by a series of heavy points placed between the 70 pointed figures and succeeded by the heavy dots, as shown; and No. 25 is the reverse of No. 24.

Nos. 26, 30, 39, 69, and 70 are representations of the Sphinx.

75 Nos. 27 and 29 are representations of statues adorning a temple dedicated to Jupiter; No. 28, a column of the Egyptian order of architecture.

No. 31 is a representation of a sacred altar.

Nos. 32 and 33 are sections which, combined, form a capital of the sixth order.

No. 34 is a capital of what has been termed the "Osiride pillar."

Nos. 36 and 37 are sections shaded upon the 85 right and left, which, combined, form an arch ornamented on its face by the pointed line with heavy dot terminations, the heavy rhomboidal ornaments, and below the terminations of the line the heavy dots.

90 No. 38 is a representation of a sphinx having the head of a ram.

No. 40 is a section of molding consisting of a light line followed by a heavy line, followed by a series of short heavy vertical lines, 95 below a heavy horizontal line followed by a light horizontal line.

No. 41 is a representation of an Egyptian flower.

Nos. 42, 43, and 44 are sections which, united, 100

form the base of a column, the face of these sections ornamented by a series of short vertical lines, some at intervals higher (so to speak) than the others, and shaded by the heavy groundwork above and below.

5 Nos. 45 and 46 are sections, similarly ornamented, to form the capital of a column.

Nos. 47 and 48 are corner-pieces for a border, the upper portions of which are inclined, 10 in one case, upon the right, in the other case upon the left, ornamented by the curved leaf-like ornaments upon a groundwork of light vertical lines, and a heavy inclined line above and a heavy horizontal line below.

15 Nos. 49 and 50 are corner-pieces for a border, the upper portions of which are concaved, ornamented by the lily-like ornaments and heavy dots shaded by the light vertical lines, and above by a heavy curved line, below by a 20 heavy horizontal line.

Nos. 51 and 55 are corner-pieces for borders formed of the Arabesque-like figures, shaded upon the face by a series of light vertical lines and the heavy horizontal and vertical lines, as 25 shown.

30 No. 52 is a volute, having at its base, upon the left, the flower-like ornament, the upper termination of the volute continued in an inclined position to form the right-hand boundary of a figure composed of a horizontal line terminating upon the right in a dot, above which is placed a short horizontal line, the space between the two lines shaded upon the left by the heavy triangular figure, which is succeeded 35 by a series of light inclined lines placed at intervals.

30 No. 53. Upon each side of a central line, terminating in a bud-like ornament, are placed the curved lily-like ornaments. The upper extremities of these meet at a central point, above which is placed an ornament formed by two curved lines, the upper extremities of which curve inward, terminating in the dots, as shown.

45 No. 54 is a center-piece, the inner central boundary of which is a semi-ring, the outer boundary the two semicircular lines, a light one shading a heavy one, the space between the heavy semicircular line and the semi-ring 50 divided by a series of inclined lines, between which are placed the heavy bud-like ornaments. Beyond the outer semicircular line are placed a bud-like ornament, succeeded by a lily-like ornament, and these are continued at 55 intervals, so that the bud-like ornaments are between the lily-like ornaments.

No. 56 is a section of a molding composed of a series of light vertical lines crossed by the heavy horizontal lines at top and bottom, or- 60 namented upon its face, about centrally, by a rhomboidal ornament, from which proceed, upon the right and left, the curved lines, the extremities of which are curved inward, terminating in the ball terminations.

65 No. 57 is a section of molding, the base of which is a heavy horizontal line shaded by a light line. Upon the left hand rises a short

curved line curving to the right, met at its upper extremity by a short curved line extending to the right and met at its right-hand termination by a curved line extending to the left, rising and curving to the right; at this termination met by a short horizontal line extending to the right until it meets a short curved line curving to the right, the outline of the portion of the figure just described shaded by a light line following its configuration, and terminating upon the left in the heavy dot, the figure shaded upon its face by a series of light vertical lines, and ornamented near the base 80 by the semicircular lines, one above the other, upon the right of which is placed the curved bud-like ornament.

No. 58 is the reverse of No. 57.

No. 59 is a section of molding composed of 85 a series of short vertical lines bounded at top and bottom by the heavy horizontal, shaded by lighter, lines, the face of the figure ornamented upon the right by a lily-like ornament. From the left-hand termination extend, above and 90 below, the curved leaf-like ornaments.

No. 60 is a group composed of leaves, bud, and flowers.

No. 61 is a corner-piece for a border, formed by two heavy vertical lines shaded by light 95 lines, meeting two heavy horizontal lines shaded by light lines, the space between the two vertical lines shaded by a series of light horizontal lines, and between the horizontal lines by a series of light vertical lines, the 100 face of the figure so formed ornamented by a lily-like ornament in a vertical position, upon each side of the stalk of which are the curved leaf-like ornaments below a ring ornamented by the four squares placed angularly to a central ring, below which outer ring the figure is continued to form the curved leaf-like ornament surmounted by the lily-buds, and is then continued, curving to the right, following the curved leaf-like ornament, followed by a ring, 110 around the center of which are placed transversely the four squares, followed by the curved petal-like ornaments. Upon the left of this ornament, and near the base of the figure, are placed the concentric rings, within which is the 115 heavy star-like figure. Upon the right hand of the corner-piece is placed a representation of the pyramids, palm-trees, and lilies.

No. 62 is a corner-piece for a border, the outline of which may be described as a heavy horizontal line met at its left-hand termination by a heavy vertical line. From its right-hand termination extends upward a short distance a curved line met at its upper termination by a heavy horizontal line extended to the left a 125 certain distance, and connected to a heavy vertical line by a heavy curved line proceeding from the left-hand termination to the base of the vertical line, this outline shaded by a light line following its configuration, the face of the 130 upper portion of the figure ornamented by a series of light horizontal lines, the lower portion of the figure extending to the right by a series of light vertical lines. Upon the face of

- the upper portion of the figure are placed the curved petal-like ornaments, between which are suspended the lines, extended about centrally, to form a rhomboid, at the base of which is the 5 ring, the face of which is ornamented by the four squares placed transversely; below this a second ring within an outer ring, within which second ring is a smaller ring having a heavy central dot, around which is placed a heavy 10 star-like figure, the space between the smaller and the next outer line shaded by a series of light inclined lines. Heavy triangular figures are placed near this ring, and to the right of it is placed, horizontally, an ornament similar 15 to that found at the upper part of the figure.
- No. 63 is the outline of the figure, as follows: At the top a heavy horizontal line, from the extremities of which proceed two heavy curved lines. These meet at their base by the heavy 20 short horizontal lines extending inward a short distance and met by the heavy vertical lines extending downward and then horizontally to the right and left and met by the heavy inclined lines extending downward to a central 25 point, the outline of the figure, save the curved lines, shaded by lighter lines following its configuration, and the figure shaded upon its face by a series of light vertical lines, and its upper portion ornamented by a ring, within which is 30 placed a star-shaped figure.
- No. 64 is a pedestal ornamented upon its face by a lily and the curved petals, and supporting a vase.
- Nos. 65, 66, 67, and 68 are groups representing grasses and leaves. Below Nos. 67 and 68 are placed moldings, the upper portion composed of heavy indented lines, the face shaded by light vertical lines, and the base a heavy horizontal line shaded by a light one.
- No. 71 is a central ornament, the upper portion a heavy horizontal line shaded by a light line, the lower portion the irregular curved lines, meeting centrally to form a semicircular line, as shown, and shaded by a light line following its configuration, the figure shaded on 40 its face by a series of light vertical lines and ornamented by a winged globe, upon each side of which is placed a heavy dot followed by the petal-like ornaments, the dots being placed 45 about centrally between the petals.
- No. 72 is the reverse of No. 61, except that the inside ornaments are composed of groups of ferns, a pillar, and an obelisk.
- No. 73 is a representation of the pyramids and the Sphinx.
- No. 74 is a representation of an obelisk, a group of flowers, and a palm-tree.
- No. 75 is a group of grasses.
- No. 76 is an Egyptian landscape.
- No. 77 is a group of leaves and flowers.
- No. 78 is a group of grasses and a palm-tree.
- Nos. 79 and 81 represent Egyptian mounds.
- No. 80 is a figure composed of leaves and lilies.
- No. 82 is a figure composed of leaves, and in 65 the center a lily.
- No. 83 represents a body of intertwined leaves.
- No. 84 represents a desert scene, as do also Nos. 91, 92, and 96.
- No. 85 is a representation of an Egyptian tomb.
- Nos. 86, 90, and 97 represent Egyptian sailing-vessels.
- No. 87 represents an Egyptian dwelling.
- No. 88 is a group of leaves.
- No. 89 is a representation of a pillar, a temple, and a palm-tree.
- Nos. 93 and 102 are groups of leaves resembling those of the grape and lilies.
- No. 94. Upon the right a representation of a palm-tree. Upon the left is placed a group of leaves and a broken pillar.
- No. 95. Upon the left a palm-tree, upon the right of which is represented a heron or stork and a body of grass or sedge.
- Nos. 98 and 99 are representations of palm-trees.
- No. 100 is a group of leaves and flowers blended together.
- No. 101 is a representation of an Egyptian sepulcher.
- No. 103 is a representation of a clump of rushes or grasses.
- Nos. 104, 105, and 110 are representations of the trunk of the palm-tree.
- No. 106 is a representation of the front of an Egyptian temple. In the distance is seen a representation of a tomb and an obelisk.
- No. 107 is a branch of the date-palm tree.
- No. 108 is a view of an Egyptian temple. In the foreground is represented a lake, an Egyptian sail-boat, and upon the right a group of banana-leaves.
- No. 109. In the foreground a crocodile; in 105 the background a group of leaves and grasses.
- Nos. 111 and 114 represent groups of leaves and a flower combined.
- No. 112 is a group of ferns and leaves.
- Nos. 113 and 116 are groups of leaves of the 110 banana-plant.
- No. 115 is a representation of the finding of the infant Moses.
- No. 117 is a representation of an obelisk, the Sphinx, the pyramids, and a palm-tree.
- Having now set forth my invention, what I 115 claim as new is—
- The design for a font of printing-types, as shown and described.

HERMAN IHLENBURG.

In presence of—

C. E. HUCH,

HERMAN METIUS.
